UNITED STATES PATENT OFFICE.

LEV. GRISWOLD, OF NEW YORK, N. Y.

SEWING-MACHINE.

SPECIFICATION forming part of Letters Patent No. 248,308, dated October 18, 1881.

Application filed September 17, 1879.

To all whom it may concern:

Be it known that I, LEV. GRISWOLD, of the city, county, and State of New York, have invented a new and useful Improvement in Sewing-Machines, of which the following is a specification.

My improvement relates to that class of sewing-machines in which a reciprocating movement at right angles to the direction of the feed is imparted to the needle-bar, which movement may be automatically varied during the operation of sewing by means of the construction hereinafter fully described and claimed.

The following is such a full, clear, and exact description of my invention as will enable others skilled in the art to which it most nearly appertains to make and use the same when taken in connection with the accompanying drawings, in which—

20 Figure 1 is a side view, showing the frame partially cut away and the mechanism within. Fig. 2 is a view of the head, showing the outer face of the face-plate, some of the parts within being shown in dotted lines. Fig. 3 is an end view of the fixed arm, showing end of shaft, eccentric, crank-lever, and lever for raising the foot. Fig. 4 is a view of the mechanism of the head cut through on the line *x x*, Fig. 1, and seen from the right of said figure. Fig. 5 is a 25 view of the mechanism of the head attached to face-plate *M'*, as seen when the face-plate is removed. Fig. 6 is a vertical section of face-plate and mechanism through the center of the needle-bar. Fig. 7 is a horizontal section 30 through a portion of the head, showing the ratchet-wheel, levers, and fulcrum-screws. Fig. 8 is a sectional view, showing ratchet-wheel, frame, pawl, arm, and link on line *y y*, Fig. 9. Fig. 9 is a side view of cam-wheel, sleeve, 35 ratchet-wheel, frame, pawl, spring, arm, and link. Fig. 10 is a bottom view of the machine, showing shuttle-race, shuttle, and a portion of the operating mechanism. Figs. 11, 12, 13, 14, 40 15, 16, and 17 show varieties of stitches made by this machine.

The machine to which my invention is applied is the two-shaft shuttle-machine shown in the drawings—a Singer machine—in which there is a rigid arm and a fixed shuttle-race 45 at right angles to the feed.

The horizontal shaft *E* in the arm *C* has motion given it by a power-belt on a pulley there-

on, and transmits motion to the vertical shaft through the beveled-gear wheels, each of equal size. The shaft *E* projects beyond the fixed 55 part *M* of the head of the machine, and has on it the eccentric *G*, which gives motion to the lever *T* and the crank-pin *H*, which works in the heart-cam *L*, and gives the vertical reciprocations to the needle-bar *I*. 60

The shuttle-race *S* is fixed to the under side of the bed-plate *A* at right angles to the direction of the feed, and has in it the shuttle *S*, to which motion is given by crank-pin *U*, rod *S*, and proper mechanism. 65

The needle-bar *I* is flat, and works within the needle-bar sleeve *K*, which is cut away on one side, excepting at the ends. To the side of the needle-bar *I* is fastened the heart-cam *L*, so that it extends a sufficient distance from 70 the side of the needle-bar *I* to allow the end of the crank *H* to pass by the needle-bar when the needle-bar oscillates horizontally, as hereinafter described.

The needle-bar sleeve *K* fits between the 75 fixed part *M* of the head of the machine on the arm *C* and the cap or face-plate *M'*, being held by a lug, *m*, on the face-plate *M'*, and is free to vibrate toward and away from the shaft *E*. The lower portion of the fixed part *M* and face-plate *M'* of the head of the machine are cut away to allow of a vibration of the needle-bar sleeve and needle-bar. 80

A spiral spring, *S*, presses against the fixed part *M* of the head of the machine and the 85 side of the needle-bar sleeve, pressing the needle-bar and needle-bar sleeve toward the face-plate *M'*. A piece of rawhide, *S*, is inserted on the inside of the face-plate, for the needle-bar sleeve to abut against as impelled by the 90 spring *S*.

The lever *O* is arranged on proper lugs on the inner face of the lower portion of the face-plate *M'*, so that at one end it will be alongside the toothed wheel *P* and at the other end alongside the needle-bar sleeve *K*, and at its center on the opposite side from that on which the wheel *P* and needle-bar sleeve *K* are, on or against the end of the fulcrum-screw *R*, which is fitted in the screw-hole provided for it in the face-plate *M'*. On turning in the screw *R* said screw comes in contact with the lever *O* at or near the center thereof, and moves said lever into contact at one end with the wheel *P* and 95

at the other end with the needle-bar sleeve K. The wheel P has on it teeth or elevations, and is connected through an axle or sleeve with the ratchet-wheel P', which latter has twice as many ratchet-teeth as there are teeth on the wheel P. The ratchet-wheel P' is caused to rotate by a lever, T, hereinafter described, which moves it one tooth at each complete revolution of the shaft E and eccentric G and each 10 complete vertical reciprocating motion of the needle-bar.

The lever O, when pressed against the wheel P so as to be affected by it, receives therefrom a vibration or oscillation complete in each two 15 complete vertical oscillations of the needle-bar and transmits such oscillations to the needle-bar sleeve by pressing said sleeve against and partially overcoming the action of the spring S.

The extent to which the fulcrum-screw R is 20 turned in or out regulates the position of the lever O in relation to the wheel P, and the extent to which the teeth thereon act upon the lever and through it overcome the action of the spring S and the consequent horizontal vibrations of the needle-bar sleeve and needle-bar. The detent-spring s bears against the ratchet-wheel P', being attached to the face-plate M', and prevents any revolution of the ratchet-wheel P', excepting in one direction, 25 as moved by the lever T. The lever T, by which the ratchet-wheel is moved, consists of two arms and the pivot-pin t, which latter is firmly attached to the lever T, and is long enough on each side of the lever to allow a back-and-forth motion (in the direction of the axis of the pivot-pin t) of the lever T and pivot-pin t. The pivot-pin t rests at either side of the lever in holes provided for it, one hole being in the fixed part M and the other in the 30 face-plate M' of the head of the machine, the holes being cut deep or recessed to allow the endwise motion of the pivot-pin t within them. The ends of pivot-pin t are long enough to allow this endwise motion without escape from the 35 holes.

The lever T is pressed by the springs t' and t'' in the direction of the axis of the pivot-pin t toward the ratchet-wheel P', so that the lower end of the lever T will bear against the ratchet-teeth of the ratchet-wheel P' or lie between them, and at the same time the lever T is pressed by the spring t'', so as to tend to turn it about the axis of the pivot-pin t. The upper end of the lever T is thus pressed against the cam G. 50 A detent-spring, s, fast to the head of the machine, catches in the teeth of the ratchet-wheel P' and prevents any backward turning of the wheel. The lever T, being pressed against the cam G by the spring t'', is oscillated about the 55 axis of the pivot-pin t by the revolution of the cam G, and being pressed against the ratchet-wheel P' the lever will be pressed between two teeth of the ratchet-wheel P' and move it when the lever T is moved in one direction, and when 60 the lever is moved in the opposite direction it will slide past the next tooth of the ratchet-wheel P', which latter is now held from turning

by the detent s, the lever being forced against the stress of the spring t' (in the direction of the axis of the pivot-pin t) by the ratchet-tooth 70 against which it bears, so that it shall pass that tooth. Thus the lever T has two motions—one of rotary oscillation about the axis of pivot-pin t, the other horizontal or sidewise sliding reciprocation in the direction of the axis of the pivot-pin t—the former being given it by the revolution of the cam G, and the latter by the oscillation of the lever past the teeth of the ratchet-wheel P' as it is held by the detent-spring s, both in connection with the action of the 75 springs t' and t''. Thus the lever T turns the ratchet-wheel P' the extent of one tooth at each oscillation.

Figs. 11, 12, and 13 show the stitch made by this machine when the lever O alone is in 80 operation to oscillate the needle-bar horizontally.

In making use of the automatic mechanism to change the fulcrum of the lever O, the fulcrum-screw R is withdrawn so as not to bear 85 against the lever O.

To the lever O, at its fulcrum, is attached the end of the lever 5 by a screw or rivet. The lever 5, at or near the end opposite to that to which the lever O is attached, passes alongside 90 of the flat cam-wheel 12, hereinafter described. At or near the center of the lever 5 the fulcrum-screw 6 is screwed in the face-plate so that its end projects through the inner side thereof and abuts against the lever 5 when turned in, 95 and presses said lever 5 against the flat cam-wheel at one end and the lever O at the other by means of the connecting screw or rivet.

The flat cam-wheel 12 is made as shown in Fig. 9, one end or side being cut at an angle a little 100 less than a right angle with the axis of the cam-wheel. The cam-wheel 12, ratchet-wheel 10, and hollow sleeve 11 are fastened together, so that their axes correspond with one another, and to them is pivoted the frame 13, so that the 105 ratchet-wheel 10 will be between the two sides of the frame.

To the frame 13 is pivoted the pawl 14, (having on it the pin 19 extending beyond the frame,) held in contact with the teeth of the 110 ratchet-wheel by the spring 15. To the frame is rigidly attached the arm 16, connected to the needle-bar by the link 17, one end of which is pivoted to the arm 16 and the other end to the 115 needle-bar by the pin 18.

The cam-wheel 12 and frame are fastened to the face-plate M' by a screw passing through the sleeve 11 into the face-plate, about which screw the sleeve and frame are free to turn independently of one another.

The cam-lever 20, having thereto attached a handle which passes through a slot in the side of the face-plate M', is held in position by the screw which passes through the sleeve 11, being free to turn about it. A spring, 22, attached to the face-plate M' presses against the handle of the cam-lever 20 and retains it in 120 any given position. The cam-lever 20 is of 125 such a form that when turned in certain posi-

tions about the screw by which it is attached to the face-plate it will project through a greater portion of the arc described by the pin 19 on the pawl 14 as it moves with the frame 13 than when said cam-lever 20 is turned in certain other positions about the attaching-screw, thereby regulating the portion of the arc of revolution through which the pawl 14 bears on or engages with the teeth of the ratchet-wheel 10.

The extent of the oscillating rotary motion of the frame 13 is the same at each stroke of the needle-bar; but by changing the position of the cam-lever 20 the distance through which the cam-wheel is turned may be regulated.

A detent-spring, 21, attached to the inside of the face-plate, engages the ratchet-wheel 10 and prevents the return of the wheel with the frame.

20 The lever O has the same oscillations on its fulcrum caused by the teeth on the wheel P, hereinbefore described, when the automatic changing-fulcrum (the lever 5) is used as when the fulcrum-screw R is used, and in addition to this the fulcrum of the lever O has motion caused by the oscillation of the lever 5, giving an oscillation to the ends of lever O, varying in extent as the lever 5 oscillates.

By changing the fulcrum-screw 6 and the 30 cam-lever 20 a variety of different forms of stitches may be made by the machine. Some are shown in Figs. 14 and 16.

On proper lugs on the face-plate is arranged the lever 30, so that one end is alongside the 35 cam-wheel 12, heretofore described, and the other end alongside the needle-bar sleeve.

Passing through the face-plate M' is the fulcrum-screw 31, at a point near the center of the length of the lever 30, and abutting against 40 the lever when screwed in. The fulcrum-screws R and 6 being withdrawn, the fulcrum-screw 31 may be turned in against the lever 30, so as to press the lever at one end against the cam-wheel 12 and at the other against the needle-bar sleeve K. The revolution of the cam-wheel 12 will cause the lever 30 to oscillate as the face of the cam-wheel bearing against it changes, making one complete oscillation at each complete revolution of the cam-wheel 12, and as it 45 always takes several vertical reciprocations of the needle-bar to make one complete revolution of the cam-wheel 12, several stitches will be taken while the needle-bar is making a complete horizontal oscillation. Any regulation 50 of the fulcrum-screw 31 will regulate the extent of the horizontal oscillation, and by the cam-lever 20 the number of vertical oscillations to one horizontal oscillation may be regulated.

Figs. 15 and 17 show specimens of the stitches 60 made by the machine when this lever 30 is in operation.

The three fulcrum-screws, R, 6, and 31, may be turned in slightly, so that all three levers will be in operation, or any two may be turned 65 in, giving as a result an irregular stitch, which repeats itself at regular intervals.

I am aware that a swinging needle-bar sleeve

and needle-bar have been used and are shown in Patent No. 184,860, of November 28, 1876, granted to me.

What I claim as new, and desire to secure by Letters Patent, is—

1. The combination, in a sewing-machine, of an overhanging arm, a fixed shuttle-race, a shuttle and mechanism for operating the same, 75 a needle-bar, a frame for carrying said needle-bar, mechanism for reciprocating the needle-bar vertically and horizontally, and mechanism for automatically varying the horizontal movement of the needle-bar during the operation of the machine, substantially as described.

2. In a sewing-machine, the combination of the sleeve 11, cam wheel 12, ratchet-wheel 10, frame 13, mechanism for oscillating said frame, pawl 14, having pin 19, a spring for insuring 85 the engagement of the pawl with the ratchet-wheel, cam-lever 20, and spring 22, for retaining said cam-lever in any given position, whereby an intermittent rotary movement may be imparted to said cam-wheel, which movement 90 may be varied as desired, substantially as and for the purpose specified.

3. The combination, with the driving-shaft E and eccentric G, of the lever T, having pivot-pin t, springs t' and t'', ratchet-wheel P', and 95 the head of the machine having recesses in which the pivot-pin t is adapted to slide and turn, substantially as described.

4. The combination, with the needle-bar I, of the needle-bar sleeve K, spring S, lever O, 100 wheel P, having teeth thereon, mechanism for imparting an intermittent rotary movement to said wheel P, lever 5, its adjustable fulcrum 6, cam-wheel 12, and its operating mechanism, whereby a horizontal reciprocating movement 105 may be imparted to the needle-bar and said movement varied automatically, as set forth.

5. The combination, with the needle-bar sleeve K, of the spring S, lever O, adjustable fulcrum R, wheel P, having teeth thereon, 110 ratchet-wheel P', a sleeve connecting said wheels P and P', lever T, mechanism for operating said lever, adjustable fulcrum 6, cam-wheel 12, sleeve 11, ratchet-wheel 10, pawl 14, spring 15, frame 13, having arm 16, link 17, 115 needle-bar I, and mechanism for imparting a vertical reciprocating movement to said needle-bar, as set forth.

6. The combination, with the needle-bar I, of the needle-bar sleeve K, spring S, levers O, 120 5, and 30, their adjustable fulcrums and mechanism for vibrating said levers, substantially as described.

7. The combination, with the needle-bar I, needle-bar sleeve K, and spring S, of the lever 125 30, adjustable fulcrum 31, cam-wheel 12, and mechanism for imparting an intermittent rotary movement to said cam-wheel, substantially as set forth.

LEV. GRISWOLD.
